UNITED STATES PATENT OFFICE.

FREDERICK J. KINDSVATER, OF AURORA, ILLINOIS.

DESIGN FOR AN AUTOMOBILE RADIATOR EMBLEM.

Application filed June 29, 1927. Serial No. 22,607. Term of patent 7 years.

To all whom it may concern:

Be it known that I, FREDERICK J. KINDSVATER, a citizen of the United States, residing at Aurora, in the county of Kane and State of Illinois, have invented a new, original, and ornamental Design for an Automobile Radiator Emblem, of which the following is a specification, reference being had to the accompanying drawing, in which—

Figure 1 is an elevation of the design as viewed from one side, and Figure 2 is a similar view from the opposite side.

I claim:—

The ornamental design for an automobile radiator emblem, as shown.

In testimony whereof I affix my signature.

FREDERICK J. KINDSVATER.
